UNITED STATES PATENT OFFICE.

ROBERT HEAD, OF NEW YORK, N. Y., ASSIGNOR TO THE AEOLIAN COMPANY, A CORPORATION OF CONNECTICUT.

TONE-CONTROL DEVICE.

Application filed August 24, 1917. Serial No. 188,020.

To all whom it may concern:

Be it known that I, ROBERT HEAD, a citizen of the United States, residing at New York, in the county of New York and State 5 of New York, have invented new and useful Improvements in Tone-Control Devices, of which the following is a specification.

The present invention has reference to tone control devices for talking machines; 10 and it comprises, briefly, an extremely simple and efficient valve mechanism, which may be readily and quickly adjusted to produce variations in the volume of sound waves passing from the sound-box of the instrument through the tone arm to the horn or amplifier, so as to effect at will any desired shading of the composition being played.

The invention further comprehends certain hereinafter described improvements in the valve itself and in its operating means, whereby a fine adjustment of the valve may be obtained by a comparatively coarse adjustment, so to speak, of the operating handle, and whereby the aforesaid valve, when once adjusted, will retain its position without danger of accidental displacement therefrom; and it also resides in the provision of a valve mechanism having the above-mentioned and other improved features, which may be manufactured and installed at comparatively low cost.

According to the illustrated embodiment of the invention, there is provided a slide 35 valve, which is mounted in a passageway formed between the neck of the horn and the tone arm socket and is shiftable forward or backward in a direction to alternatively cover or uncover the opening through which the sound waves enter the horn. The valve is constructed in such a way as to completely avoid leakage around it, and, also, as to frictionally maintain its position at any point in its travel; and it is operated by means of 40 a device, the component parts of which are so adjusted and proportioned that a very gradual motion of the valve in approaching or leaving its closing position is provided for, so that an abrupt shutting off of the sound-waves or vice versa, with resultant 45 inharmonious break in the tone, is avoided even though the handle or other actuating part be carelessly manipulated.

In the accompanying drawing:

55 Figure 1 is a plan view of a talking machine equipped with the improved tone control valve and operating means therefor.

Figure 2 is an enlarged vertical section, taken on line 2—2, Figure 1.

Figure 3 is a horizontal section, taken on line 3—3, Figure 2, showing the valve and its mounting.

Figure 4 is an inverted perspective view of the valve.

Referring more particularly to said drawing, 5 indicates generally the cabinet of the machine, 6 the top shelf thereof, and 7 the tone arm carrying the sound-box 8, all of which parts are, or may be, of the usual construction. The downwardly-curved rear end 70 of the tone arm 7 has the usual rotating fit in the socket 9, which latter may be mounted in the shelf 6 in any desired manner and communicates directly with the horn 10 to provide for the passage of the sound-waves 75 through said tone arm from the sound-box and thence into and through the horn.

In the construction herein disclosed, which may, for all practical purposes, be considered as preferred, the improved valve 80 11 is located at the junction of the horn and tone arm socket, and is fitted to move endwise in either direction in a horizontal slide-way 12, which is formed partly by each of the two elements just mentioned. For this 85 purpose, the confronting ends of said elements are enlarged so as to provide oppositely-located upper and lower flanges 13 and 14, which are spaced slightly apart by means of their vertical side edges 15, said 90 flanges being fastened to each other by screws or the like. Hence, it follows that the sound passage is intersected at right angles by the slide-way 12, which is open at opposite ends but closed along its sides, so 95 that the movements of the valve in one direction or the other will serve to regulate the effective area of said passage at such point and, consequently, the volume of sound waves passing therethrough.

The aforesaid valve, as here shown, is designed to fit conformably in the slide-way 12, and is preferably composed of a lower, sheet metal member 16, and an upper member 17 made of leather or other suitable sound-obstructing material, the two members being cemented or otherwise fastened together. The valve is made substantially rectangular, and has a U-shaped piece cut out of its front end, leaving an opening 18, the width of 110

which is equal to the diameter of the sound passage at the point where the socket and the horn meet, while the rear portion of the edge or wall of said opening has approximately the same curvature as the adjacent wall of the sound passage. The length of the opening is such that the two arms 19 produced consequent upon its formation are enabled to extend beyond the sound passage 10 and rest upon the far side of the slideway for all positions of the valve. In addition to the said opening 18, the valve is provided with a second opening 20, which is located at the rear of the first or end opening and 15 likewise has a diameter substantially equal to that of the sound passage; but the second opening 20, instead of being formed through both members of the valve, extends solely through the lower or metal member thereof, 20 leaving the upper or leather member exposed therethrough, and it is this exposed portion, indicated in Figures 3 and 4 at 21, which closes the sound passage when the valve is in its fully closed position.

25 The valve is shifted from one position to another by means of an adjusting device which comprises a manually-operated part and a motion-reducing means, the latter being located intermediate the manually-operated part and the valve and connected with both of them. The reducing means is here represented as consisting of a wire rod 22 having one end thereof fastened to an eye provided on the adjacent end of the metal 30 member of the valve, and a crank arm 23 to which the other end of the rod is secured. The crank arm is directly attached to the manual part, and is swung or turned thereby, said part consisting, in the present instance, of a horizontal rock shaft 24, journaled in bearings provided in the front and rear walls of the cabinet and equipped at its projecting front end with a button or handle 35. The crank arm 23 is adapted to move 40 through an arcuate path of about 90° ; and, in the closed position of the valve, it projects horizontally to the right from the rock shaft, this position of said arm being indicated in dotted lines in Figure 2. When the valve is fully open, the said arm projects directly downward, the valve being almost but not quite fully open in the position depicted in Figure 3, as will be understood.

45 By reason of the construction and arrangement above described, it will be apparent that the rod 22 will move endwise in one direction or the other, according as the handle 25 is moved in one or the other direction, said rod being pushed forward or to the right to close the valve and being pulled back to the left to open it. Also, the movement of the valve slows up as it approaches its fully-closed position, due to the fact that the crank-arm 23 becomes more nearly 50 aligned with the direction of movement of

the slide-valve. This means that when the operating knob 25 is given an ordinary, relatively uniform rotary movement or twist to close the valve from its open position in Fig. 2, said valve will slide to the right with a non-uniform movement which will be relatively rapid during the first part thereof but which will become gradually slower until it becomes very slow and gradual somewhat prior to and at the moment of its complete closing. Similarly, on the reverse operation of the knob 25, the valve will at first very slowly open up communication between the tone-arm and horn, its movement becoming increasingly rapid as it approaches fully-open position. Since most of the volume of tone will be transmitted by a relatively small opening, it will be seen that it is important that the first part of the opening movement and the last part of the closing movement should be slow and gradual as aforesaid, in order to prevent abrupt changes in the volume of the sound. On the other hand, when the valve is in a more nearly open position, such for instance as three-quarters or two-thirds open, a relatively large, quick movement of the valve has relatively little effect on the volume of tone; and therefore during this stage in the movement of the valve, it is not only not detrimental but actually advantageous to have the valve move quickly. The foregoing ideal movement for the purpose of the valve is automatically accomplished by the operator. Further, a comparatively coarse adjustment of the operating knob 55 produces a fine adjustment of the valve, especially at the stage in its movement, when, as above explained, a fine adjustment is the most desirable.

60 In order to retain the valve in any position to which it may have been moved by means of the devices above described, the arm portions 19 of the metal member are slit longitudinally, as shown in Figure 4, and the outer sections thereof are bent slightly downward, so as to form the spring fingers 26. The inner or rear portions of the aforesaid member is also slit at opposite sides to provide similar fingers 27, and these two pairs of fingers 26 and 27 bear upon the bottom wall of the slideway 12 with sufficient force to hold the valve against accidental displacement. At the same time, the pressure thus imposed by the said fingers upon the slideway wall serves to push the valve in an upward direction, thereby bringing its non-metallic upper member into contact with the upper wall of the slideway; the result, therefore, is that a tight joint is formed between the valve and the walls of the slideway which completely preclude leakage of the sound-waves around the side edges of the valve.

65 I claim as my invention:—
1. In a musical instrument, the combina-

- tion, with a sound conduit, and a slideway intersecting the same; of a valve in said slideway movable across said conduit to control the passage of the sound waves there-
5 through; adjusting means for said valve; and spring fingers acting against said valve adjacent to opposite edges thereof and against said slideway to retain the valve in adjusted position.
- 10 2. In a musical instrument, the combination, with a sound conduit, and a slideway intersecting the same; of a valve in said slideway movable across said conduit to control the passage of the sound waves there-
15 through; and adjusting means for the valve; said valve comprising a sheet metal member which is provided with integral spring fingers engageable with said slideway to retain the valve in adjusted position.
- 20 3. In a sound-reproducing instrument, the combination with a sound conduit; of a valve movable across said conduit to control the passage of sound therethrough, said valve comprising a member having a pair
25 of longitudinally spaced openings therein arranged so that one of said openings is brought into communication with said conduit concurrently with the movement of the other opening in a direction to carry it out
30 of communication with said conduit, and a vibration-deadening medium covering one of said openings.
4. In a sound-reproducing instrument, the combination, with a sound conduit, and a
35 slideway intersecting the same; of a valve in said slideway movable across said conduit to control the passage of the sound waves therethrough; and adjusting means for the valve; said valve comprising a member of
40 vibration-deadening material and a supporting member provided with spring fingers engageable with the slideway to retain the valve in adjusted position and to force the member of vibration deadening material into
45 contact with the adjacent wall of the slide-
way.
5. In a sound-reproducing instrument, the combination, with a sound conduit, and a slideway intersecting the same; of a valve in
50 said slideway movable across said conduit to control the passage of the sound waves therethrough; said valve comprising super-
posed layers of vibration-deadening ma-
terial and supporting material therefor, both
having an opening formed therethrough
adapted to register with said conduit, and
the supporting material only having an
opening therein adjacent the first-named
opening to expose the vibration-deadening
material across the sound-conduit when the
valve is in closed position.
6. In a sound-reproducing instrument, the combination, with a sound conduit, and a slideway intersecting the same; of a valve in said slideway movable across said conduit to control the passage of the sound waves therethrough; and adjusting means
65 for the valve; said valve comprising a mem-
ber composed of vibration-deadening ma-
terial and a supporting member provided
with spring fingers engageable with the
slideway to retain the valve in adjusted po-
tion and force its member of vibration-
deadening material into contact with the up-
per wall of the slideway; both members hav-
ing their front portions cut away to provide
an opening adapted to register with said con-
duit, and the supporting member only hav-
ing an opening in rear of the first-named
opening to expose the vibration-deadening
material extending across it.
7. In a musical instrument, the combination with a sound conduit, and a slideway intersecting the same; of a valve in said
75 slideway movable across said conduit to con-
trol the passage of the sound waves there-
through; said valve comprising superposed
layers of vibration-deadening material and
supporting material therefor, the support-
ing material but not the vibration-deadening
material having an opening formed there-
through so that when the valve is closed sub-
stantially only the vibration-deadening ma-
terial registers with the opening in the con-
duit.
8. A tone modifier plate comprising a cut-
off board and a pair of spring runners po-
sitioned beneath opposite edges of said
board, the whole formed from a single strip
of sheet material.

In testimony whereof I have hereunto set
my hand.

ROBERT HEAD.
